DESIGN FOR A SHOULDERETTE

Lorna Whittingham, San Francisco, Calif.

Application August 12, 1941, Serial No. 102,797

Term of patent 3½ years

To all whom it may concern:

Be it known that I, Lorna Whittingham, a citizen of the United States of America, residing in San Francisco, county of San Francisco, and State of California, have invented a new, original, and ornamental Design for a Shoulderette, of which the following is a specification, reference being had to the accompanying drawing, forming part thereof.

Fig. 1 is a front view of a shoulderette showing my new design.

Fig. 2 is a rear view thereof.

My design comprises a shoulderette consisting of two closed sleeves with openings at the cuff and shoulder portions and connected by a bow at the neckline as shown.

I claim:

The ornamental design for a shoulderette, substantially as shown and described.

LORNA WHITTINGHAM.
